TRUCK TIPPING MECHANISM WITH INITIAL LIFT LEVER

Charles R. Golay, Cambridge City, Ind.

Application February 13, 1948, Serial No. 8,168

3 Claims. (Cl. 294—22)

1

This invention relates to new and useful improvements in elevating or tipping hoists which are particularly, though not specifically, designed for adaption to the dumping body of a vehicle.

The primary object of this invention resides in the provision of a tipping hoist for vehicle dumping bodies which employs a hydraulic ram as the source of power for elevating the body. Economy of space is a requisite of such a hoist when it is supported beneath a dumping body by the vehicle frame, therefore it is necessary that the ram lie in a substantially horizontal plane bounded above and below by the vehicle body and frame respectively. It is, therefore, another object of this invention to provide a hydraulic ram hoist for vehicle dumping bodies which satisfies the requisite of space economy by folding compactly between the frame and body when inoperative, yet providing such a hoist apparatus which is sufficiently efficient to accomplish its desired result.

It is common knowledge that the first portion of the body tipping elevation is the most difficult to manage as it is during that portion, before the load weight is shifted beyond the point of support, that the load is the heaviest. Because of the original horizontal disposition of the hydraulic ram coupled with the extreme weight characteristic of the load to be lifted from this original position it is necessary that the hoist apparatus be of an extremely heavy and oversize construction, or a means must be provided to aid a smaller, low pressure ram in the primary elevation of the dumping body. It is, therefore, another object of the present invention to provide a booster mechanism which operates in conjunction with the ram assembly during the primary lifting stage to such a point in the angle of elevation of the body as to place the ram in a sufficiently raised position above the horizontal so that it may complete the tilting operation without the necessity of high pressure and extreme oversize apparatus.

Still another object of this invention lies in the provision of a tilting hoist assembly as set forth which is of an extremely simple and durable construction which may be manufactured and installed at a relatively small expense.

Still further improvements and advantages of this invention will readily appear to those skilled in the art when the specification and claims are read in the light of the accompanying drawings.

In the drawings:

Fig. 1 is a perspective view of the assembled hoist.

Fig. 2 is a view in side elevation of the hoist, vehicle frame and body in a normal lowered position.

2

Fig. 3 is similar to Fig. 1 with the body and hoist in an intermediate elevated position.

Fig. 4 is a view similar to Fig. 3 illustrating a greater elevated position of the parts and illustrating the modified roller track.

Fig. 5 is a perspective view of the modified roller track.

With reference now to the drawings accompanying this specification which illustrate the preferred embodiment of this invention, and in which like characters indicate similar parts throughout, A designates the frame, or sub-frame, of a vehicle which has a dumping body B supported on side sills 1. The sills 1 are pivoted conventionally at the rear ends thereof, as at 2, to the rear end of the frame in a manner permitting the forward end of the body to be elevated above the frame about the pivot 2.

A pintle 4 is rigidly supported transverse the frame A intermediate the length thereof. A pair of channel bars 3 are revolvably suspended from adjacent ends thereof and in opposed, spaced apart relationship on the pintle 4. A pin 5 rigidly interconnects the lower, second adjacent pair of ends of the bars 3 retaining them in parallel positions. A second pair of channel bars 6 are secured one to each of the upper ends of the bars 3 to extend at approximately a 30 degree angle from the longitudinal center line of the bars 3. These second bars 6 are rigidly interconnected at their extremities by a second pin 7 on which is centrally, revolvably supported a large metallic roller 8. Thus the combination of the centrally pivoted pairs of parallel, opposed channel bars form an elongated lever.

A hydraulic ram cylinder C provided with a reciprocating ram piston 9 is provided as the power source for the hoist apparatus. The base end of the cylinder is revolvably secured on the pin 5, which is supported between the lower ends of the bars 3. The outer end of the reciprocal ram piston 9 is secured in a fitting 10 which is rigidly carried at the longitudinal center of an elongated tubular housing 20.

A pair of cylindrical arms 21 are telescopically inserted one in each end of the tubular housing 20, and each of these arms are provided with rigidly secured L-shaped plates 22 at their outer extremities.

The plates 22 are secured one to each of the spaced body sills 1 at such a distance rearward along the body from the pintle 4 so as to place the piston 9 in a fully retracted position in the cylinder C when the body is in its normal, lowered, horizontal position. When the body is in the described lowered position, as illustrated in Fig. 2, the cylinder C will be substantially horizontally disposed and the lower ends of the

channel bars 3 will be forwardly and upwardly pitched at substantially 30 degrees from the horizontal to dispose their integral bars 6 in a horizontal position forwardly from the pintle 4.

It is the centrally pivoted lever formed by the pairs of channel bars 3 and 6 which act as the elevating booster to aid the ram in tipping the dumping body.

When fluid is admitted to the cylinder C through a flexible tubing 30, from an external source, the increased pressure will tend to cause an extension of the ram piston 9. However, the weight of the body will cause, instead of a projection of the piston, a rearward movement of the cylinder of a force equal to that attempting to project the piston.

The rearward movement of the cylinder will cause a depression of the lower end of the bars 3 and a corresponding elevation of the rearwardly extending ends of the bars 6.

As the arms 6 continue to rise the roller 8 will contact a roller plate 31, carried longitudinally beneath the body, and an upward and rearward force will be exerted beneath the body causing a tilting elevation thereof.

Because the forward end of the body is furtherest from the pivoted connection of the body and the frame that end will be the more easily lifted, thus the cylinder will continue to move rearwardly rather than extending the piston until the arms 3 are brought to vertical positions at which time they firmly abut with a beam 32 secured transverse the frame A.

When the arms 3 abut with the beam 22 the bars 6 have been elevated to a position of substantially 60 degrees above the horizontal and likewise the body has also been elevated to an intermediate lift position. At this time the cylinder is restricted from further rearward movement, and at this time the ram piston begins its projection to complete the elevation of the body, which has been elevated sufficiently to place the cylinder at an angle above the horizontal great enough to permit it to easily raise the body through its remaining tilting angle.

Naturally, the lowering of the body is a converse operation to that just described for raising the body.

The modification set forth in Figs. 4 and 5 is directed to a modified roller track which comprises an inverted channel bar 40 which is secured longitudinally beneath the underside of the body. This inverted channel bar 40 is secured beneath the body above the free end of the channel bars 6 in such a manner and position so that the roller 8 carried by these bars 6 will contact a rearwardly, angularly depending plate 41 which is rigidly secured longitudinally beneath the channel bar 40.

After the roller is moved into contact with the rear end of the plate 41 it will then move forwardly over the plate and as the roller is raised through its remaining arc of elevation it will travel over the downwardly inclined plate and will cause an elevation of the body which is increased over the elevation caused by the original structure by an amount equal to the angle included between the plate 41 and bar 40.

The specific means for supplying hydraulic pressure for operating the ram forms no part of the present invention. The source of supply could be a power driven means carried by a tractor or other vehicle or a manually or power operated supply means could be mounted on the

dumping vehicle itself. The placement and manner of operation of the fluid pressure supply means would be controlled by the particular circumstances existing.

From the foregoing description of the embodiments of this invention it may be readily seen that a structural means has been provided for incorporation with a straight push ram type of dumping body hoist which permits a reduction in the size and pressure requirements of the mechanism yet which increases the efficiency of the hoist in its functional operation. It may also be readily seen that the structure of the hoist apparatus comprising the embodiment of this invention is of a durable and sturdy design which may be manufactured and installed at a relatively inexpensive cost.

With full belief that I have contemplated all modifications of this invention which fall within the scope of the appended claims what I desire to claim in Letters Patent is:

1. An elevating hoist for vehicle dumping bodies comprising, in combination, a vehicle frame, a dumping body supported on the frame and pivoted thereto transverse the rear end thereof, a pintle supported transverse the frame intermediate the length thereof, a lever composed of a pair of bars rigidly joined to form an obtuse angle therebetween, said lever revolvably supported on the pintle at the juncture of the two bars comprising the same, a hydraulically operable extensible ram, one end of said ram being revolvably supported on one end of the lever, the other end of the ram being revolvably secured to the underside of the body rearwardly from the lever, a roller plate supported longitudinally beneath the dumping body vertically aligned above the lever, a roller revolvably supported by that end of the lever remote to the ram, a lever engaging stop carried by the frame substantially in vertical alignment beneath the lever pivot, and means for operating the ram to extend the same.

2. A structure as defined in claim 1 wherein, said lever and said ram are substantially horizontally disposed when the body is in its lowered position, with that end of said lever supporting the roller being forwardly disposed relative to the vehicle.

3. A structure as defined in claim 1 wherein, the roller plate is provided with depending side edges which form between them a channelway for the reception of the lever carried roller, a second plate having an end in the channelway, and said second plate extending downwardly and rearwardly toward the rear of the body, the parts operating whereby the lever carried roller can transverse the channelway and from it roll onto the second plate.
